UNITED STATES PATENT OFFICE.

WILLIAM R. MILLER, OF BALTIMORE, MARYLAND.

DESIGN FOR A BOTTLE.

SPECIFICATION forming part of Design No. 15,213, dated August 5, 1884.

Application filed May 21, 1884. Term of patent 14 years.

To all whom it may concern:

Be it known that I, WILLIAM R. MILLER, a citizen of the United States, residing in the city of Baltimore and State of Maryland, have 5 invented and produced a new and original Design for Bottles, of which the following is a specification, reference being made to the accompanying drawings, forming a part hereof.

Figure I is a perspective view, Fig. II is a 10 front view, Fig. III an edge view, and Fig. IV an under side view, of the bottle.

According to my design the exterior shape 15 of the bottle is as follows: The base A of the bottle is of rectangular form with beveled corners, as at a, and the sides B extend vertically from the base. The top C of the body is spheroidal, and the neck D is as large in diameter as the width of the bottle will admit of. Viewed

from the side, as in Fig. II, the bottle has a square face, bordered at the sides with the 20 beveled edges and a spheroidal top. The bottle as seen from the edge, as in Fig. III, presents a rectangular face, bordered with the beveled edges and a spheroidal top. The neck has the usual band, b, at its edge. 25

What I claim is—

A design for a bottle, which consists of a rectangular bottom having two of its parallel sides longer than the remaining two sides, with beveled corners, vertical sides, and a spheroidal 30 top, as herein shown and described.

WM. R. MILLER.
